UNITED STATES PATENT OFFICE

147,327

DESIGN FOR A BABY CARRIAGE OR
SIMILAR ARTICLELouis Gottfried, New York, N. Y., assignor of
one-half to Jakob Berger, New York, N. Y.

Application April 19, 1946, Serial No. 128,793

Term of patent 14 years

(Cl. D14—14)

To all whom it may concern:

Be it known that I, Louis Gottfried, a citizen of the United States, residing at city of New York, in the county of Bronx and State of New York, have invented a new, original, and ornamental Design for Baby Carriage or Similar Article, of which the following is a specification, reference being had to the accompanying drawing, forming part thereof.

This application is a continuation-in-part of my design patent application Ser. No. D121,010, filed July 27, 1945.

In the drawing:

Figure 1 is a perspective view of the baby carriage or similar article showing my new design, as it appears in fully extended position;

Fig. 2 is a perspective view of the baby carriage or similar article of Fig. 1 as it appears in lowered or collapsed position, the handle being also in lowered position.

Fig. 3 is a plan view of the part of the carriage as shown in full lines in Fig. 1.

The characteristic features of my design reside in the portions shown by means of full lines in the drawing.

I claim:

The ornamental design for a baby carriage or similar article, as shown and described.

LOUIS GOTTFRIED.
